QUENCHING DEVICE FOR DRILL STEELS

Filed Jan. 28, 1928

FIG. - 1.

INVENTOR.
Charles C. Hansen
BY *Charles C. Hansen*
HIS ATTORNEY

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

QUENCHING DEVICE FOR DRILL STEELS

Application filed January 28, 1928. Serial No. 250,287.

This invention relates to quenching devices, but more particularly to a quenching device for drill steels.

It is an object of the present invention to assure uniform quenching of heated articles and to prevent the formation of air bubbles on the surface thereof during the quenching operation and consequent soft spots in the body of the hardened article.

10 Other objects will be in part obvious and in part pointed out hereinafter.

The invention consists of the combination of elements and arrangement of parts having the general mode of operation substantially as hereinafter described and claimed and illustrated in the accompanying drawings, in which—

Figure 1 is a side elevation, partly in section, of the quenching unit, and

20 Figure 2 is a sectional plan view of a detail taken through Figure 1 on the line 2—2 looking in the direction indicated by the arrows.

Referring to the drawings, A designates a 25 tank containing quenching liquid B which may be introduced in the tank A through an opening C. An overflow pipe D connected to the tank A serves to maintain a constant level in the tank and conveys any excess liquid 30 to the source of supply (not shown).

The tank A in this instance is supported by a foundation E which also serves as a support for a pump F communicating with the tank A through a pipe G. Any suitable 35 prime mover may be utilized for actuating the pump F. In the drawings a motor H connected to the pump by means of a belt J is used for this purpose.

The pump F may be of any suitable type 40 and has a discharge pipe K which preferably extends over the tank A. In the discharge pipe K is interposed a casing L having a chamber O through which the liquid flows from one section of the discharge pipe K to the other. In the present instance the casing L is raised somewhat above the tank A and a branch pipe P is connected to the casing for conveying liquid from the chamber O to the tank A.

50 The casing L is provided with a manually

operable valve Q which in one position covers the entrance to the branch pipe P, thus directing liquid from one section of the discharge pipe K to the other, and in another position, cuts off communication between the sections of the discharge pipe connected to the opposite end of the casing for directing the liquid B from the discharge pipe into the tank A.

55 Suitable means are provided for converting the liquid into a spray and for directing such spray on the heated end of a working implement, as for instance, the bit R of a drill steel S. These means comprise a nozzle body T threaded to the end of the discharge pipe K and a nozzle cap U secured to the nozzle body by means of bolts V. The nozzle cap U preferably has a dome-shaped projection W which extends into a cavity X in the nozzle body T and in its outer surface 60 has a socket Y to receive and support the bit end R of the drill steel S.

65 In order to direct the liquid in the cavity X on the bit R of the drill steel and to reduce such liquid into the form of a spray, 70 the dome-shaped projection W is provided with a plurality of small apertures Z which converge toward the axis of the socket Y so that the spray issuing therefrom will come into direct contact with the entire surface of 75 the heated article, such as the bit R of the drill steel. The nozzle body T is preferably provided with additional supporting means other than the discharge pipe K and in this instance a frame b is mounted on the top of 80 the tank A and the nozzle body T is secured to said frame by means of bolts c.

85 The operation of the device is as follows: Whenever it is desired to quench the heated bit of a drill steel, said bit may be inserted 90 in the socket Y whereby it will be maintained substantially coaxially with the point of convergence of the apertures Z. With the pump F in operation, liquid will be pumped from the tank A through the discharge pipe 95 K into the cavity X from whence it will issue through the apertures Z against the heated drill bit under pressure. In view of this fact, the fluid will strike the drill bit with considerable force and will prevent the 100

formation of air bubbles on the heated surface. The bit R will therefore be hardened uniformly.

While the liquid is thus being forced through the apertures Z, the valve Q of course occupies a position to prevent the flow of liquid from the casing L into the tank A. After the drill bit has been quenched, however, the valve Q may be 10 rocked into a position to prevent the flow of liquid into the cavity X and liquid pumped into the chamber O of the casing L will then flow therefrom through the branch pipe P and be returned again to the tank A.

As will be readily appreciated, the pump F may be in continuous operation and the course of the liquid may be controlled entirely by proper manipulation of the 20 valve Q.

The present invention is particularly adapted for drill steels of great length. Such steels are not only difficult to maneuver into a position to immerse the drill bit 25 into the ordinary type of quenching tank but, due to the angle at which it is necessary to insert such drill steels, one side of the heated bit of necessity enters the liquid before the other, with the consequence that uneven hardening of the drill bit takes place. The present invention completely overcomes 30 the aforesaid difficulties. It is inexpensive to install and to maintain, and assures uniform hardening of the drill bits.

35 I claim:

A quenching device, comprising a nozzle body having a cavity for quenching liquid, a nozzle cap adapted to be secured to the nozzle body, a dome-shaped projection on the 40 nozzle cap extending into the cavity and having a cylindrical socket to support an article intended to be quenched, and a plurality of radially arranged apertures in the projection to introduce jets of liquid into 45 the socket and converging on the longitudinal axis of the socket to assure uniform quenching of such article.

In testimony whereof I have signed this specification.

50 CHARLES C. HANSEN.
